UNITED STATES PATENT OFFICE

LOUISE EASTON WESTING, OF NEW YORK, N. Y., ASSIGNOR TO DOROTHY GRAY, OF BLOOMFIELD, NEW JERSEY, A CORPORATION OF NEW JERSEY

RECEPTACLE

Application filed September 9, 1930. Serial No. 480,738.

The invention relates to receptacles and has as an object the provision of a receptacle adapted to contain the various cosmetics demanded by ladies.

5 A further object of the invention is to provide a receptacle having compartments especially designed to carry a variety of cosmetics, lotions and the like.

It is a further object of the invention to 10 provide a receptacle of the character described having provision for carrying the cosmetics which may be desirable to transport when traveling.

15 Further objects of the invention will appear from the following description when read in connection with the accompanying drawing showing an illustrative embodiment of the invention and wherein:—

Figure 1 is a perspective view of the receptacle with the cover in open position.

20 Figure 2 is a perspective view of a form of liquid container to be carried in the receptacle.

Figure 3 is a plan view with the cover open.

25 Figure 4 is a central vertical section with the cover closed, and

Figure 5 is a plan view of a tray adapted for use in the receptacle.

30 As shown, the device comprises a case 10 shown as cylindrical in form and a cover 11 adapted to telescope with the top of the case 10 and provided with a flexible leather hinge 12 and braces 12' to support the cover in open position. There is shown a strap 13

35 passing over the top of the receptacle having an end 14 passed through a perforation 15 in the wall of the receptacle adjacent the hinge 12 and secured as at 16 by securing means which may be common to the end 14 and to an end of the hinge 12. The strap 13 is shown as secured to the cover at 17 and

40 18 to provide a handle for the receptacle, the end of the strap being provided with one portion of a latch 19 by which the cover may be secured in closed position.

45 A mirror 20 is shown secured upon the interior of the cover as by means of a retaining ring 21. To carry containers for a variety of cosmetic creams and the like, there are shown sockets 22, in the base of the con-

tainer which sockets are shaped to fit the jars in which the creams are packaged. To contain liquids of which a greater quantity is usually desired than of the creams, there is shown a pair of sockets 23 equipped with bottles 24 extending the full height of the casing, the bottles 24 being formed with a flattened side 25 for a purpose to be described.

55 The sockets 23 are shown as provided with 60 collars or sleeves 26 to provide additional support for the bottles and to serve as a support for a portion of the weight of a tray 27 shown in plan view in Figure 5. The tray 27 is shown as arcuate in a portion 65 of its periphery to fit within the casing 10 and as flattened at 28 to permit of the projection upward therebeyond of the bottles 24. The jars in the sockets 22 are of such a size and the sockets of such a depth as to 70 bring the tops of the jars level with each other and with the tops of the sleeves 26, as clearly shown in Figure 4, by which arrangement the bottom of the tray 27 may be 75 carried upon the covers of the short jars with one edge resting upon the upper edge of sleeves 26. The tray 27 is shown as formed 80 with a recess 29 to contain a box as of powder and with other recesses 30, 31 to contain small packages of rouge or a compact.

85 The tray 27 is shown as provided with a pair of loop handles 32 which may be secured to the inner surfaces of the recess 29.

By virtue of the flattened portions of the bottles 24, the tray is allowed to overlap portions of the interiors of the sleeves 26 to secure more positive support of the tray. The projection upward past the tray, of the bottles 24, enables access to these bottles containing the most used cosmetics or lotions, without removal of the tray.

90 There is thus provided an exceedingly attractive and simple beauty case which is equipped to carry the variety of cosmetics desired by a lady, when traveling.

95 Minor changes may be made in the physical embodiment of the invention without departing from the spirit thereof.

I claim:

1. A receptacle comprising, in combina- 100

- tion, a casing having a plurality of sockets interiorly of its bottom, containers seating in certain of said sockets and of less height than said casing, a tray of less area than the cross section of said casing and resting on said containers, a container seating in a remaining socket rising substantially to the upper edge of the casing and extending upwardly past said tray.
10. 2. A receptacle comprising, in combination, a casing having a plurality of sockets interiorly of its bottom, containers seating in certain of said sockets, the depth of said certain sockets and the height of said containers being so related as to cause the tops of the containers to fall substantially in the same plane, a tray having container receiving sockets, said tray of less area than that of the cross section of the casing and resting on said containers, and a container seated in a remaining bottom socket and rising past said tray to substantially the top of said casing.
3. A receptacle comprising, in combination, a casing having a plurality of sockets interiorly of its bottom, containers seating in certain of said sockets with their tops substantially in a common plane, hollow sleeves seating in other of said sockets with their upper edges lying in said plane, a tray fitting with a portion of the inner surface of said casing and supported partially on said containers and having a non-fitting edge lying on the upper edges of said sleeves, containers in said sleeved sockets rising past said tray and removable without disturbing said tray.
4. A receptacle comprising, in combination, a substantially cylindrical casing having sockets interiorly of its bottom, containers in certain of said sockets with their tops substantially in a common plane, sleeves seating in the remaining sockets with their upper edges in said plane, a tray fitting with a portion of said casing and supported partially upon said containers and partially upon said sleeves, the non-fitting portion of said tray flattened to lie in a vertical plane overlapping the inner surfaces of said sleeves and containers in said sleeved sockets having flattened portions rising past the flattened portion of said tray substantially to the top of said casing.

LOUISE EASTON WESTING.
